SYSTEM OF FINISHING SHOES

Myron O. Frost, St. Louis, Mo., assignor, by mesne assignments, to The Lamson Company, Syracuse, N. Y., a corporation of Massachusetts

Application August 24, 1931, Serial No. 558,925

1 Claim. (Cl. 12—142)

This invention relates generally to the manufacture of shoes, and particularly to a system of arranging the various machines and operators in the so-called finishing department of a shoe factory in order that the shoes may be advanced progressively from one operator to the next.

It has heretofore been the practice in shoe factories that each individual operator be provided at his operation station with an individual case or rack of shoes, it being the usual practice to employ a rack of such size to transport an entire case of shoes. With an arrangement of this sort it is apparent that any particular time in a shoe factory there are relatively few shoes which are being operated upon although there are a great number tied up at the various operator stations. Furthermore, it has been heretofore the general practice that when it is necessary to permit a rack of shoes to temper or permit the cement thereon to set, the rack containing these shoes have, as a general rule, been set aside in an available space in the shoe factory and consequently a great portion of the space in a shoe factory is occupied with idle racks of shoes, which were either being dried or else being delivered at a particular operator's station. It is an object of the present invention to overcome the difficulties encountered in the usual process and of manufacturing shoes mentioned above and this invention contemplates a coordination of systems by which the shoes may be advanced individually throughout the various systems and from one operator to the next succeeding operator immediately upon completion of the operation at the first operator's station.

The object of this invention generally stated is to provide a system of manufacturing shoes, and particularly a finishing department through which the shoes may be progressed without delay.

Another object of this invention is to provide a system for operating upon shoes through which the shoes may be advanced individually upon completion of a particular operation.

A further object of this invention is to provide a conveying system operating adjacent the various operators of a finishing department of a shoe factory.

A more specific object of this invention is to provide a system and arrangement of the operators in the finishing room of a shoe factory in which the number of operators for performing relatively rapid operations is less than the number of operators performing relatively slow operations.

Other objects will become apparent to those

skilled in the art when the following description is read in connection with the accompanying drawings, in which:

Figure 1 is a diagrammatic plan view illustrating the arrangement of operator stations in a system for finishing the soles of the shoes.

Figure 2 is a diagrammatic plan view illustrating the arrangement of operator stations in a system for finishing the bottoms and otherwise operating upon shoes.

Figure 3 is a diagrammatic plan view illustrating a system for finishing shoes and particularly the arrangement of operators for treeing, polishing and repairing.

Generally stated, in accordance with this invention the various operator stations of a shoe factory are preferably disposed adjacent suitable conveying devices, such as for instance, belt conveyors, chutes and the like, and in cases where the operations to be performed are relatively slow, it is preferable to provide a series of operators who perform these operations. On the other hand where the operations to be performed may be accomplished with substantial rapidity, a fewer number of operators may be provided for performing the operations. In accordance with this invention suitable conveyors are preferably so disposed that the output of the series of operators may be converged at the station of a fewer number of operators whose operations are accomplished with relative rapidity. This invention further contemplates the provision of conveying drying units suitably disposed in positions where tempering or setting of the cement or other so-called dopes are necessary, whereby the operator who applies the substance to be dried may deposit individually the shoes upon such a drying unit for the next succeeding operator who removes the same as it comes in position adjacent the latter station. Furthermore, in many instances and particularly in the finishing department of the shoe factory, it is necessary that the shoes of one type be delivered in position for the performance of various operations which are not necessary with other types of shoes and accordingly this invention contemplates the provision of suitable conveyors and a corresponding arrangement of operators whereby the shoes are permitted to move through the most direct path to their destination.

Referring now particularly to the drawings for an illustrative embodiment of this invention, the shoes proceed to the finishing room as a general rule from the wooden heel attaching room of the shoe factory. During the application of

wooden heels to shoes it is customary to provide a coating of cement between the heel and the heel seat, and it is consequently of importance that this cement should have opportunity to set before the shoes are subjected to finishing operations. Accordingly, as the shoes are completed by the wooden heel attaching department they may be deposited in a suitable drier, such as 1 entering, for instance at 2, and after remaining a desirable period of time, making their exit at 3, it being understood that the drier, if so desired be provided with suitable mechanism for advancing the shoes therethrough. It is convenient in many instances to rack the shoes heretofore practically before placing the same in the drier 1 and it will be understood that suitable mechanism may be provided for advancing the various racks of shoes through the drier and the speed of such advancing mechanism may be regulated in order to permit the shoes to remain within the drier for the desired or appropriate period of time. After the shoes have remained in the drying unit 1 for a sufficient time to permit proper tempering or setting of the cement the various racks, such as 4, may be removed therefrom and advanced into position adjacent the system for finishing the soles to be now described.

The shoes contained in an individual rack, such as 4, may be distributed among a series of sole edge trimmers 5 positioned adjacent a suitable conveyor preferably of the duplex type as 6, and preferably provided with a central dividing partition, such as 7. It may be pointed out that in a system of this sort a single rack of shoes may be divided among a series of four edge trimmers 5, for instance the right shoes being supplied to the operators positioned on the right hand side of the conveyor, and the left 40 shoes being supplied to the operators on the left hand side of the conveyor, and vice versa. Moreover, with a provision of a conveyor of this sort, it is apparent that the operators on one side of the conveyors may be supplied with shoes from a different rack or case than the rack or case which supplies the operators on the other side of the conveyor, in which case the central dividing partition 7 will be operated to maintain the shoes from the different cases in segregation.

After the series of operators 5 have completed their operations, which generally consist in an edge trimming operation upon the sole in order to properly shape the same, the shoes may be deposited on a suitable chute or conveyor, such as 8, preferably provided with a central dividing partition 9. As illustrated in Figure 1, the conveyor or chute 8 is shown as disposed directly beneath the conveyor or chute 6, it being observed that the conveyor or chute 8 extends forwardly for a sufficient distance to make it convenient for each of the series of trimmers 5 to deposit their respective output therein. The chute or conveyor 8 conducts the shoes from the trimmers into a position convenient to one of a series of setters 10, it being observed that there is provided but one setter for each pair of trimmers in view of the fact that the setting operation requires but approximately one-half the time required for trimming the shoes. As the shoes are advanced into a position convenient for the setters 10, the setters may remove a small number of the shoes from the chute or conveyor 8 and apply the usual first dope thereto, depositing the same for a brief period (sufficient

to dry the dope) upon a suitable table or shelf 11. For instance each setter may remove from the chute or conveyor 8 as many as six pairs of shoes, doping the same successively and depositing the same upon the table 11. After the last shoe of the sixth pair has been doped, the dope applied to the first shoe of the first pair is dry enough to permit the setter to proceed with the setting operation. If, however, as is often the case, certain types of shoes happen to come through the factory which require a more lengthy first set than a shoe of the ordinary type, an additional operator may be provided at station 12 for doping the shoes which proceed down both sides of the conveyor or chute 8 so that, in this instance, it is unnecessary for either the series of setters 10 to apply the dope.

After the setting operation has been completed the operators stationed at 10 may deposit their output upon a suitable chute or conveyor 13 also provided with a central dividing partition 14. The shoes are removed from the chute or conveyor 14 by an inker 15 who applies to the edges of the sole an appropriate dye or ink and deposits the same upon a suitable drier (such as 16 for instance 16, which may be of the conveying type, and is preferably provided with a dividing line or device, such as 17, in order that shoes proceeding from separate cases or conveyor 13 may be maintained in segregation on the drier 16). After the shoes have remained upon the drier 16 for a sufficient time and have come into position adjacent the opposite side of the drier 16 they may be removed therefrom by one of the series of setters 18, whose duty it is to apply the second set to the edges of the soles and upon the completion of these operations the shoes may be deposited in a suitable rack, such as 19; it being understood that in case separate cases of shoes are proceeding down opposite sides of the conveyor there will be provided an individual rack adjacent the individual operators 18.

From an inspection of Figure 1, it will be apparent that a unit 20 is provided, which to all intents and purposes, is a duplicate of that just described in detail. The unit 20 illustrates the flexibility of the system, such as for instance to allow for pillars of the building, such as 21, it being apparent that the various operators may be slightly spaced in order to accommodate such obstructions.

After the shoes have been deposited upon the rack 19 by one of the series of setters 18, the shoes may proceed to a suitable drying unit, not shown, in order to properly temper the same before proceeding to the bottom finishing system now to be described.

After the rack 19 has remained for a sufficient time in the tempering or drying unit, just referred to, it may be removed therefrom and moved into position adjacent an edge brusher 22, Fig. 2, who may remove the shoes from the rack 19, brush the edges thereof, and deposit the same upon a chute or conveyor 23 also of the duplex type, and provided with a central dividing partition 24. With some shoes it is necessary to perform a scouring operation upon the sole immediately in front of the breast of the heel, and, if such an operation is necessary, the shoes may be passed by operator 22 over to a breast scourer 25 who upon completion of his operation deposits the shoes upon a chute or conveyor 23. The chute or conveyor 23 operates to convey the shoes into position where they are available to one of a series of finishers, such as for instance the bot-

tom sanders 26. In view of the fact that there are two such bottom sanders provided, it is often convenient that one sander handle all the lefts and the other all the rights, it being understood that the bottom sanding operation to be performed by a series of operators 26 requires substantially twice the amount of time for operation as the edge brushing operation and the breast scouring operation. There are provided in the illustrated embodiment a series of bottom sanders while there is provided but one edge brusher.

In order to avoid a possibility of one of the bottom sanders 26 missing or skipping a shoe disposed upon the chute or conveyor 23, the bottom sander 26 is deposited for work upon a suitable chute or conveyor 27 disposed on the opposite side of these operators from the position of the chute or conveyor 23. The output of the bottom sanders 26 then proceeds down conveyor 27 to a position convenient for the various operators who perform different finishing operations such as for instance an edge buffer 28 and the shank finishers 29 who may be provided with a suitable flexible shaft buffer. Each of the finishers just referred to preferably redeposit their work upon the conveyor upon completion of the respective operations and the work then proceeds to a position convenient for a series of shank buffers 30 who upon completion of their operation preferably deposit the work upon a suitable chute or conveyor 31, preferably provided with a center line or partition 32 in order to maintain the shoes of different cases in segregation as will be pointed out hereinafter. As the output of the shank buffer 30 proceeds down conveyor 31 it may be removed therefrom by breast scourer 33 whose duty it is to scour the heel leaf or flap and further finish the same. Upon completion of these operations at 33 the shoes may be redeposited upon the conveyor 31 from which they may be removed from operator stationed at 34 who may perform further sanding operations where necessary, and brush the shoes, deposit the same upon a suitable conveyor as 35 preferably of the duplex type and adapted to maintain the separate cases of shoes in segregation.

It will be observed from Figure 2 that the arrangement of operators just described is provided in duplicate, and, it is to be understood that like reference characters denote stations at which the same operations are performed upon different shoes. It may be pointed out, however, that different cases or racks of shoes are preferably supplied to the units on opposite sides of the central conveyor 23 which, it will be recalled, is provided with a device, such as for instance the dividing partition 24, for maintaining the shoes in different cases for segregation as they proceed therealong. Upon reaching the bottom sanders 26 of the duplicate units, however, the shoes are preferably removed from the center conveyor and deposited upon the individual conveyors 27 extending along the outside of the respective units, while upon reaching the shank buffers 30 of the duplicate units, the shoes may again be converged upon a central conveyor 31, being maintained in segregation by positioning the shoes from one unit at one side of the central dividing partition 32 and the shoes from the other unit upon the other side of the center line 32.

The shoes proceed from the operators 34 down conveyor 35 to a position convenient for one or

more operators stationed at 36 whose duty it is to apply various treating substances to the shoe soles, such as for instance a polisher or blackener. After the application of such substance, the shoes are positioned upon a suitable drier, such as 37, preferably of the conveying type, and after remaining upon the drier for a desirable period of time may be removed by an operator stationed at 38, who may inspect the bottoms and apply an additional coating of a suitable substance where necessary, whereupon the shoes may be disposed upon a suitable drier, such as 39 preferably also of the conveying type. After the shoes have remained upon the drier 39 for a desired period of time they may be removed therefrom by an operator, such as 40 who may, if necessary, brush the edges of the shoes before depositing them upon a conveyor, such as 41, which, as illustrated, is preferably provided with markings or ribs to denote three separate rows or aisles therealong. For instance shoes, the bottoms of which are to be of the natural grain, are generally treated with a gum and may be consequently deposited upon the conveyor 41 in one of the outside rows 42. The conveyor 41 transports the shoes to a position convenient for either of a series of gummers 43 who may remove the same from the conveyor, apply the gum and preliminarily buff the same depositing their respective output upon a suitable drying conveyor, such as 44. As the drying conveyor 44 advances the shoes toward the left, the gum applied by the operators 43 becomes sufficiently dry to polish, and accordingly upon reaching a position adjacent the polisher 45 the polisher removes the shoes from conveyor 44 and polishes the same, depositing his output upon the conveyor 46.

If, however, the shoes removed by the operator 40 happen to be shoes which are provided with a black bottom, the same may be deposited upon a conveyor 41 in the center aisle 47 thereof, and transported to a position convenient for a burner 48, who removes the shoes from the conveyor, burnishes and polishes the bottoms and returns the same to the conveyor. Similarly, shoes with a paint bottom after being removed from the drier 39 may be deposited upon the conveyor 41, and since there remains nothing further to be done, except polishing, paint bottom shoes may be conveyed directly across the conveyor 41 without any interruption. It is generally preferred than an operator 49 be stationed adjacent the end of conveyor 41 for removing therefrom the shoes which proceeded thereacross, and such operator may be provided with a suitable brush for brushing white shoes, which at times will proceed across the conveyor. In view of the fact, however, that the shoes of a particular type will proceed from the drier 39 in lots, such as for instance an entire case at a time, it will be apparent that at such times as the burnishers 48 may be busy polishing black bottom shoes, as a general rule one of the gum polishers will be idle and accordingly may occupy position 49 for removing the shoes from the center conveyor 41 and deposit the same upon conveyor 46. Similarly, it will seldom happen that both of the exterior aisles 42 and the central aisle 47 of the conveyor will be concurrently filled with shoes which require further treatment, such as for instance shoes to be gummed, in the exterior aisle and black shoes in the interior aisle 47, and it is apparent, therefore, that when black shoes proceed down at center aisle 47, say the gummers of series 43 disposed on one side of the

conveyor, or those disposed on the other side, will be idle and consequently these idle operators may move into position of the burnishers 48 and handle the black shoes which proceed down the center aisle 47 of the conveyor 41, while the corresponding polisher 45 may move into position 49 for transferring the shoes from the center aisle 47 on to the conveyor 46. It is apparent, therefore, that such shoes as do not require polishing by the polisher 45 may be shunted around the conveyor 44 and the polisher 45 by means of the conveyor 47 so that the shoes in fact proceed in the most direct and shortest route to the conveyor 46. The shoes are then transported by the conveyor 46 in a direction indicated by an arrow and upon reaching the end thereof may be removed by a screw puller stationed at 50 who may remove the temporary heel-attaching device from the last and deposit the work upon a suitable conveyor as 51.

The conveyor 51 transports the shoes to a position convenient for a series of last pulleys 52 disposed upon opposite sides of the conveyor 51 who remove the last from the shoes and return the shoes to the conveyor. Adjacent each of the last pulleys 52, a suitable elevator or other last receptacle 53 may be provided, such elevator may operate to return the lasts automatically to the room in which the last bins are situated.

After the delasted shoes have been returned to the conveyor 51 by the last pullers 52 they are transported to a position convenient for the series of heel nailers 54, it being generally preferable that the series 54 disposed upon one side of the conveyor 51 handle the shoes of one case, while the nailers disposed on the opposite side of the conveyor 51 handle the shoes from a different case. If the particular shoes which are being operated upon by the nailers 54 are formed of delicate fabrics or skins in which case the shoes are usually during the course of manufacture protected by a suitable cover, the nailers may return the shoes to the conveyor 51 upon completing their operation thereupon. In this case the shoes will be transported to a position convenient for cover cutters 55, who may remove the shoes from the conveyor 51, remove the covers and pass the shoes across their table to lining ironers disposed at 56 whose duty it is to iron the linings of the shoes and deposit the same upon suitable racks as 57, or upon other suitable conveying devices for transporting the same into a position convenient for the performance of the next succeeding operation.

In the event, however, that the particular shoes being operated upon by the nailers 54 are not provided with the usual protector covers, the nailers may deposit their output upon an outside conveyor 58 which operates to transport the same in the direction indicated by the arrow to a position convenient the lining ironers 56 for shunting the shoes about the cover removers 55.

When one of the racks, such as 57, has been completely filled with shoes the same may be moved into position convenient for a series of sock liners 580 who may remove the shoes from the rack and insert therein the usual sock linings. In the illustrated embodiment shown it is often convenient that one of the operators insert the sock lining in the left shoes, while the other handles the right shoes. Operating adjacent the sock liners 580 a suitable conveyor 59 may be provided for receiving the shoes from the sock liners. From the embodiment illustrated in the drawings 70 two conveyors, such as 59, are shown which are

sufficiently spaced from each other so that operators may be stationed therebetween. It is accordingly provided a series of trimmers 60 disposed to receive work from the respective conveyors 59, it being understood that the trimmers 60 may be provided with suitable trimming machines, such as for instance the well-known Booth trimmer. If the shoes be of fancy type which require that further cutouts be made, the same may be deposited in a suitable chute as 61. One such chute being conveniently stationed adjacent each of the series of trimmers 60. As illustrated in the drawings a chute 61 may be and preferably is, disposed immediately above the conveyor 59. Situated on each side of the chute 61 and the conveyor 59 operating therebeneath a series of operators 62 are provided for accomplishing such cutouts as are necessary, it being understood that the operator 62 either effects such cutouts by hand or by any suitable machine, it being understood that the cutting out operation performed by the operator 62 is a relatively slow one. Many shoes pass through the ordinary shoe factory which does not require that such cutouts be made. The chute 61 being of sufficient length, allows a substantial number of shoes requiring cutting out to accumulate therein without blocking the system. For instance, if a case of shoes requiring several cutouts reach the Booth trimmers 60, the same may be deposited upon completion of the operation in the chute 61 and in view of the fact that the time required for the trimmers 60 is substantially less than the time required for the accomplishment of the cutting out operation by operator 62, the shoes requiring cutouts may accumulate in the chute 61. After the trimmers 60 have completed their operation upon the entire case of shoes, it may be possible that a case will come through the system which will require no cutouts, in which instance the shoes will be redeposited upon conveyor 59 upon completion of the trimming operations by trimmers 60 so that even though the chute 61 be completely filled with shoes requiring cutouts, the system is, nevertheless, still capable of handling shoes which do not require cutouts to be made. After the operators 62 have completed the cutting out operation necessary, they may return the work to the conveyor 59 from which it may be removed by one of a series of singers stationed adjacent the end row. In view of the fact that the singeing operation requires little time, the singers 63 have sufficient time to deposit the shoes on rack 64 or other conveying device to transport the shoes into the next succeeding department of this factory.

After the shoes have been racked by the singers 63 the rack 64 may be moved into the department illustrated in Figure 3, and the racks moved into positions adjacent a series of suitable shaping machines 65. As shown in Figure 3 one such rack as 64 may be moved into position adjacent a pair of shaping machines, one of which is adapted to shape the left shoes, the other the right shoes. These shaping machines operate to press the upper at the counter and sides against a form in the shoe.

After the shaping operation has been completed upon an entire rack of shoes, the rack may be moved into position 66 adjacent one of the series 70 of operators 67, each of which is provided with a brush and buffing roll device for cleaning and polishing the shoes. The operator 67 may remove the shoes from the racks in position 66, performing his operations thereupon and depositing 75

them upon a suitable duplex conveyor, such as 68. If the shoes proceed down conveyor 68 they may be removed therefrom by one of a series of trees disposed in pairs on opposite sides of 5 the respective conveyors, it being understood that in view of the fact that a different tree must be employed for treeing left shoes from the tree which is employed for treeing right shoes, one operator of each pair may conveniently operate 10 exclusively upon left shoes, the other exclusively upon right shoes. The tree 69 performs the usual washing and ironing operations upon the shoes, employing any suitable treeing device. Upon completion of these operations the shoes 15 may be redeposited upon conveyor 68 by which they will be transported into position adjacent a shining station 70, after which they may be redeposited upon conveyor 68 and will proceed to a series of cleaning and dressing stations, such 20 as 71 and 72, it being understood that any suitable number of stations for performing the different dressing operations customary in a particular factory may be provided adjacent the conveyor 68. The last of the series of operators, such as 25 72, in the illustrated embodiment, may, however, deposit the shoes upon a suitable rack, such as 73, or other conveying device for moving the same into convenient position for the next succeeding operation. The rack 73 may then be 30 moved into position, such as 74, adjacent a series of repairers 75 arranged in pairs and adjacent a suitable duplex conveyor, such as 76. The respective repairers of each pair are preferably so positioned that one operator of each of the pairs 35 may remove sufficient shoes from the rack 74 for supplying each operator of the pair. Accordingly some of the time all of the repairers 75, remote from the conveyor 76, are occupied in passing shoes from the rack 74 to the inside repairers or those which are nearer the conveyor 40 76, but on the other hand, substantially the same amount of time of the inside repairers, or those nearest the conveyor 76 are occupied in passing the work from the outside to the conveyor 76. The 45 various repairers 75 inspect the shoes and touch up any of the bruised places with suitable inks and dies in order to bring the bruised or marred leather as near as possible to its original condition. Upon completion of these operations the 50 inside operator of each pair of repairers 75 deposits the output of the repaired work upon conveyor 76 by which it is transported to a position convenient to one of the singers 77 whose duty it is to singe away the loose threads from the 55 shoes, and due to the fact that such an operation requires but little time, the singers may distribute the work among a series of secondary conveyors 78 and 79 each of which is preferably of the duplex type, it being understood that at this 60 point the various types of shoes proceed to have individual operations performed thereupon, which are by no means common to all the various types. For instance, the conveyor 78 may be adapted to transport shoes of the patent leather type to 65 operating positions such as 80, where operations may be performed which are not necessary upon other types of shoes.

The various other types of shoes may, however, be deposited upon conveyor 79, adjacent which 70 may be provided with a series of operators 81 for dressing the white shoes, a series of spraying operators 82, a series of breast cleaners 83 for operating particularly upon box heel shoes, and any 75 number of other operators for performing operations which are not common to all the various

types of shoes, and which are necessary before the completed shoes may be delivered to the packing room. For instance, if the shoes are of such types as require the attachment of ornaments, the same may be racked at the end of the conveyor 79 and moved into position such as 84, adjacent a series of ornament-attaching machines 85. On the other hand, if the shoes require the stitching of buckles or center straps the shoes requiring these operations may be separately 10 racked and moved into position adjacent machines for performing these operations, which may be stationed in any suitable position. Again, if the shoes require only lacing, after emerging from the conveyor 79 the racks may be moved into 15 position adjacent an operator's station 87 where the laces may be applied, and upon application of the laces the shoes may then be deposited upon a suitable conveyor 88 and transported past a series of skilled trimmers and inspectors 89 whose 20 duty it is to closely inspect the shoes passing thereby and perform such trimming operation as necessary. After the shoes have passed the trimmers and inspectors 89 the same may be deposited upon a table 90, where the shoes will be assembled in boxes and prepared for packing, being subsequently put in the shipping cases and thence delivered to the shipping room as by suitable conveyor 91.

From the foregoing description it is apparent that the invention accomplishes its operations and that a system of manufacturing shoes is provided which is made up of a plurality of sub-systems such as, for instance, a system for finishing the soles, a system of finishing the bottom 35 and otherwise operating upon the shoes as nailing the heels in positions after the performance of a number of finishing operations, and finally concluding with a system of trimmers, polishers, and repairers, in which the final touches are given 40 the shoes before proceeding to the packing room. However, all these respective sub-systems are so arranged and coordinated that the output of one sub-system may proceed directly to the next without delay. Accordingly the time required for 45 manufacturing of shoes in accordance with the present invention is considerably shorter than that heretofore required. Moreover, it is apparent that many modifications of the system of manufacturing shoes hereinbefore described and 50 illustrated in the accompanying drawings will present themselves to those skilled in the art which will not depart from the spirit of this invention. It is to be distinctly understood, therefore, that the invention is not limited to the 55 specific details hereinbefore set forth, but that such modifications or the use of such individual features or sub-combinations of features as do not depart from the spirit of this invention are, although not specifically described herein, contemplated by and within the scope of the appended claim.

In this specification reference has been had to various machines or devices designated in accordance with the operations they are to perform; such as sole edge setters, trimmers, etc. Such machines or devices are well known and in common use in various shoe factories and are illustrated in various catalogues, as well as patents, to which reference need not be 70 had in order to enable those skilled in the art to obtain a disclosure of the system embodying this invention. In many cases the various operations may be performed by hand and, in some cases, are performed by hand. It is, there- 75

fore, to be understood that where any operation is referred to it contemplates not only a machine but also a station at which an operator may be positioned to perform the operation.

6 Having thus described the invention, what is claimed is:

The art of manufacturing shoes wherein the shoes are progressively assembled by operators at stations, certain operations only being performed upon the shoes at each station, which comprises transporting the shoes between two stations and to a third station upon a conveyor on which the shoes are separated into three lots, one

lot destined for each station, transporting each of the lots of shoes destined to said first two stations after treatment thereat to fourth stations, respectively associated with each of said first two stations, by other conveyors independent of each other and of the first named conveyor, transporting the lots of shoes despatched to the third station and to each of said fourth stations to a fifth station by a conveyor on which the lots of shoes are kept separate, and after treatment at the fifth station, removing the shoes therefrom.

MYRON O. FROST.
